UNITED STATES PATENT OFFICE.

CLYDE J. COLEMAN, OF NEW YORK, N. Y., ASSIGNOR TO CONRAD HUBERT, OF NEW YORK, N. Y.

ENGINE-STARTER.

No. 867,796.

Specification of Letters Patent.

Patented Oct. 8, 1907.

Application filed November 12, 1906. Serial No. 342,999.

To all whom it may concern:

Be it known that I, CLYDE J. COLEMAN, a citizen of the United States, residing in the borough of Manhattan, in the county of New York and State of New York, have invented certain new and useful Improvements 5 in Engine-Starters, of which the following is a specification, reference being had therein to the accompanying drawings, forming a part thereof.

My invention relates generally to starting devices 10 for non-self-starting engines, more particularly internal combustion engines such as are used on automobiles or other motor vehicles, and has for its objects large capacity and great power combined within a small compass, adaptability to various styles of engines and vehicles, durability, simplicity of construction, and reliability of operation.

Other objects and advantages will appear from the following description.

My invention includes means continuously operating 20 while the engine is running to store power in a hydraulic power storing device at a relatively constant and less rate than power is used from the power storing device during an engine starting operation.

My invention also includes a power or pressure reservoir 25 for containing liquid under air pressure, a motor operatively connected to the engine shaft for rotating the shaft and starting the engine, a directional clutch being interposed between the engine shaft and the motor, thus permitting the engine shaft to rotate independently of the motor after the engine has been started, a manually operable supply valve for admitting the 30 liquid from the pressure reservoir to the motor, a receptacle for receiving the exhaust liquid from the motor, and a continuously-acting pump driven by a moving 35 part of the engine, for returning the liquid from the receptacle to the pressure reservoir.

My invention also includes means, automatically operated by the engine, for forcing air into the pressure reservoir, thus keeping up the stored power by maintaining the air pressure in the reservoir at a maximum, the pressure reservoir being provided with a blow-off 40 valve, to prevent the pressure therein from rising above the maximum, the pressure reservoir also being provided with an automatically closing valve, so as to always 45 retain enough liquid in the pressure reservoir to form a seal and prevent the escape of the compressed air through the service outlet provided for the liquid.

My invention also includes means operative when the pump cylinder and the passages therebeneath have 50 become filled with air, owing to all of the accessible liquid having been taken out of the receptacle, to first remove such air by an outlet independent from that provided for the liquid and leading to the reservoir, when liquid is present in the receptacle, such means 55 comprising an arrangement of valves which permits

the passage of air outward from the pump cylinder while preventing such passage of liquid.

My invention also includes means for starting the engine directly with a crank, in the ordinary manner, and also, by a separate operation, recharging the pressure reservoir with liquid by the use of the same crank. 60

The embodiment of my invention illustrated will now be described by reference to the accompanying drawings, after which I will point out my invention in claims. 65

Figure 1 is a partial central horizontal section of the motor and pump and adjacent parts. Fig. 2 represents a crank for applying directly to the engine shaft or to the pump, through the central aperture, shown in Fig. 1, in the casing. Fig. 3 illustrates a screw-cap for closing the central aperture in the casing. Fig. 4 shows the motor and pump in elevation, a portion of the casing being broken away. Fig. 5 is a plan view, on a greatly reduced scale, of the complete device attached to a motor vehicle, for starting the engine thereof. Fig. 6 70 is a substantially full sized vertical central section of the pressure reservoir, showing also the manually operable supply valve and its operating lever. Fig. 7 is an enlarged front elevation of the motor and of the clutch by which the motor is coupled to the engine shaft, certain parts being broken away and certain other parts removed. Fig. 8 is a sectional plan about on the line $x-x$ of Fig. 7. Fig. 9 is a vertical section about on the line $y-y$ of Fig. 7 as viewed from the right. Fig. 10 shows one of the motor vanes as viewed from the outer 75 end. Fig. 11 is a side view of one of the vanes of the motor, showing the side to which the working pressure is applied. Fig. 12 is a view of the inner end of one of the motor vanes. Fig. 13 is an enlarged partial vertical section of the pump and the means by which it is operated. Fig. 14 is an end elevation of the same as viewed from the right of Fig. 13. Fig. 15 is a section on the line $z-z$ of Fig. 13 and shows the manner of arrangement of the stems and guides of the liquid-outlet and air-inlet valves. 80

In the device of this invention the power for starting the engine is supplied by having a suitable liquid, such as oil, confined in a reservoir under the pressure of compressed air contained in the reservoir above the level of the liquid, the liquid from the reservoir being 85 supplied, through a manually operable valve, to a motor which is connected by a clutch to the shaft of the engine, the clutch automatically disengaging from the motor when the engine shaft is driven by the engine itself, and there being a continuously-acting pump, 90 driven by the engine, for returning the used liquid back to the pressure reservoir, and means also being provided for keeping up the air pressure within the pressure reservoir. 95

In the drawings, the reservoir 1, for containing the oil 110

or other suitable motive liquid and also containing the compressed air within which the power is stored for impelling the liquid, is shown in Fig. 5 as secured to the side frame of a motor vehicle. A pressure supply pipe 2 leads from the pressure reservoir 1 to the motor within the casing 3 at the front of the vehicle, and a return pipe 4 leads from the pump within the casing back to the pressure reservoir, these pipes forming conduits for the motive liquid shown as contained in the reservoir. The pipe 2 connects respectively the liquid outlet 5 of the reservoir with the inlet port 6 of the motor, and the pipe 4 connects respectively the discharge outlet 7 of the pump with the inlet 8 of the reservoir. The motive liquid is normally prevented from escaping from the reservoir by reason of the valve 9, working in the valve chamber 10 and seating upon the valve seat 11. The stem 12 of the valve 9 passes out through a packing gland 13 and is connected by a pin 14 with a manual lever 15 pivoted at 16 to a bracket 17, the valve being normally held upon its seat by a strong retractile spring 18, shown as connected to the lever at one end and its other end to the reservoir by a band 19 having a lug 20. To secure a firm and close seating of the valve 9, it is shown as provided with a face plate 21, which may be of celluloid. The spring 18 should be strong enough to hold the valve 9 seated against the pressure from the reservoir 1. The object of having the valve 9 open outwardly is to give unobstructed egress to the motive liquid. The valve 9 may be opened by moving the lever 15 toward the right, as seen in Figs. 5 and 6, and against the tension of the spring 18, the valve being thus manually held open while the engine is starting, after which the lever is released and the valve is closed by the action of the spring 18. When the valve 9 is open the motive liquid is forced from the reservoir 1 through the outlet 5 and supply conduit 3 to the motor for starting the engine, which motor will now be described. However, it may first be noted that while the starting motor is at the front of the vehicle, the pressure reservoir may be located at any other suitable point, and also that the operating lever 15 may likewise be located at any point found most convenient for manipulation, either contiguous to the pressure reservoir, as shown, or at some other point.

The motor is shown as comprising a rotary piston 22 rotatably mounted upon a clutch member 23 fixed, as by a key 25, upon the engine shaft 24. The clutch member 23 has spurs or teeth 26, each having a radial side and an inclined side, gripping rollers 27 being located between the teeth. The gripping rollers 27 are shown as restrained against accidental lateral displacement and loss, by side plates 44, shown as attached to the member 23 by screws 45 entering holes 46. In Fig. 7 these plates 44 are removed, but may be seen in Fig. 5. The rotary piston itself forms the other clutch member, the rollers 27 acting in a well known manner to grip the piston 22 and thus lock the two clutch members together against relative rotary movement in one direction, while freely permitting such movement in the opposite direction.

From the above it is apparent that when the piston 22 is rotated in a clockwise direction, as seen in Figs. 4 and 7, it will rotate the shaft 24 along with it, but that if the shaft 24 be independently rotated in the same direction the piston 22 will not be rotated therewith.

The piston 22 is provided with radial pressure-receiving vanes 28 sliding radially in slots 29 in the rotary piston 22. The vanes 28 are prevented from escaping from the slots 29 and the radial movement therein is limited by screw pins 30 whose heads at the outer limit of movement of the vanes, engage with shoulders 31, in grooves 32, the screws or pins 30 also forming guides for the vanes 28 and preventing their lateral displacement relatively to the piston 22. The vanes 28 are normally held at their outward limit of radial movement by springs 33 seated in sockets 34 in the vanes and reacting against the bottom of the slots 29. To permit of the vanes 28 being acted upon by the motive liquid, a partial casing or housing is provided, comprising side plates 35 extending at the sides of the piston 22 to below the bottoms of the slots 29 and covering, as shown, about one-fourth of the circumference of the rotary piston. The housing comprises also a circumferential block 36, shown as clamped between the blocks 35 by bolts 37. To push the vanes 28 radially inward against the downward tension of the springs 33, the block 36 is provided with an inclined nose 38, and to thus hold the vanes inward and to prevent leakage of the motive liquid the block has a curved surface at 39 conforming to the circumference of the rotary piston 22 and of a circumferential length not less than the distance between two of the vanes 28. To permit of the vanes 28 being acted upon by the motive fluid the block 36 is provided, forwardly from the curved surface 39, with a second curved surface 40 conforming to the circular path of the outer ends of the vanes 28 when the vanes are in their projected or extended phase, and of a length not less than the distance between two vanes, thus always presenting a sealed condition of the passage between the two plates 35 and between the surface 40 and the circumference of the piston 22. The block 36 is also provided, intermediately of the curved surfaces 39 and 40, with a radially inclined surface 41 joining the two curved surfaces 39 and 40 and providing a gradual incline down which the vanes 28 may travel as they move from retracted to extended positions. The inlet port 6, for the motive liquid, pierces the block 36 and opens on the inclined surface 41, the surface 41 thus forming an abutment against which the motive liquid reacts to drive the vanes 28 along the passage which is upwardly bounded by the surface 40, thus causing the piston 22 to rotate. To produce a balanced condition of the vanes 28, they are provided on the rear face with grooves 42 which allow the motive liquid to pass into the slots 29 beneath the vanes. In order that this balanced condition of the vanes shall exist at the time when they should begin their radially outward movement, notches 43 are provided in the surface 41, the notches 43 registering with the grooves 42 and admitting motive liquid thereto prior to the beginning of the travel of the vanes along the surface 41, thus insuring that the vanes will not be thrown suddenly outward against the surface 40.

From the above it is apparent that when the motive liquid is admitted through the port 6, by the actuation of the lever 15, the motor, as illustrated, will be rotated in a clockwise direction, and, by reason of the interposed clutch, will rotate the shaft 24, and thus start the engine. It is also apparent that when the engine is started the clutch will become disengaged or opera-

tively disconnected as soon as the engine speeds ahead of the motor. As soon as the engine starts the lever 15 may be released thus shutting off the supply of motive liquid from the motor and stopping the motor, the engine shaft continuing to freely rotate while the motor is stationary.

It should be noted that my invention is not dependent upon the particular type of motor above described, but includes the employment of any suitable type of 10 motor whatever, that illustrated being merely an example of a suitable motor used to carry out the complete invention.

The motor is shown as supported upon a cross-piece 47, which may be attached to the frame of the vehicle, 15 as shown. To avoid the necessity of exact alinement of the motor the engine shaft is preferably provided with flexible couplings 48 and 49, as shown in Fig. 5. The engine shaft 24 has a bearing 50 in the cross-piece 47 and the clutch member 23 has an integral sleeve 51 20 which has a bearing in a bar 52 forming a part of the frame for the motor.

The casing 3 is attached to a back plate 53, as by screws 54, a gasket 55 being interposed between the casing 3 and the plate 53 to make a liquid-tight joint. 25 Leakage is prevented around the bearing 50 by a clamping nut 56, shown as screwed thereupon. The casing 3 is provided with a central aperture 57, for which is provided a liquid-tight screw-cap 58. From the above it is apparent that the motor is inclosed within a liquid-tight receptacle or casing. When the motive liquid or 30 exhaust is discharged from the motor it is received within this casing which surrounds the motor, and which thus constitutes the receptacle or receiving tank for such exhaust liquid, the motor when in operation, 35 freely rotating in this contained liquid. It should be understood that this casing that forms the receiving tank is not hermetically sealed, the exhaust liquid therein being only under atmospheric pressure.

In the foregoing it has been shown how the engine 40 would be started, it having been assumed that the reservoir 1 contains a motive liquid under pressure of a confined elastic fluid such as air. That part of the mechanism for returning the motive liquid, after it has been used in the motor, to the pressure reservoir, and for 45 keeping up the pressure in the pressure reservoir, will now be described.

The motive liquid is taken up out of the receiver and returned to the pressure reservoir by a continuously-acting pump comprising a vertically disposed cylinder 50 59 and a reciprocating plunger 60. The cylinder for the pump is supported in a fixed position by screws 61 passing through holes 62 and attaching it to the part of the motor frame 52. Whenever the engine is running the plunger 60 will be continuously reciprocated by 55 reason of a lever 63, shown as connected thereto by a pivot-pin 64, the lever 63 having a fulcrum-pin 65 carried by arms 66, shown as integral extensions from the pump-cylinder 59. The lever 63 is actuated in one direction, corresponding to the working stroke of the 60 plunger 60, by a cam 67 which is compelled to rotate with the shaft 24 of the engine, the end of the lever upon which the cam acts being provided with an anti-friction roller 68. The lever 63 is actuated in its opposite direction of movement, corresponding to the suction stroke of the piston or plunger, by a coiled spring

69, acting between the lever and one of the supporting arms 66. The cam 67 is driven by the shaft 24 through the medium of ratchet teeth 70 on the cam and which engage with ratchet teeth 71 on the end of the sleeve 51 of the clutch member 23, these coacting ratchet-teeth 70 being held in engagement by a spring 72 coiled about the shaft 24 and held under compression by a pin 73 so as to press upon the side of the cam opposite to the ratchet-teeth. The purpose of this ratchet connection of the cam 70 with the shaft 24 will be described presently, it only being necessary at this time to take note that the cam 67 is positively driven in a forward, or, as shown, clockwise direction by the engine shaft 24. The pump cylinder 59 has at its bottom an inlet opening 74 and also has at its lower part a laterally extending and upwardly turned conduit 7 forming a discharge or outlet opening. The inlet 74 is shown as provided with an ordinary check-valve 75 held in place by a pin 76. A suction-pipe 77 connects with the inlet 74 and extends to a point near the lowest part of the exhaust-receptacle or receiving tank formed within the casing 3. The upwardly turned portion of the outlet 7 is connected to the discharge or return pipe 4. It is provided with a lift or check valve 78 which, to guard against leakage, under high pressure, is seated upon a ring 79. 90

The pump is of much smaller capacity than the starting motor, and therefore the motive liquid will be returned from the casing 3 to the reservoir 1 at a correspondingly less rate than it was discharged or used by 95 the starting motor in the engine starting operation, thereby making the load on the engine for recharging the reservoir 1 so light as to be negligible. As the pump operates continuously while the engine is running the motive liquid will be returned to the reservoir 100 1 at a constant rate relatively to the speed of the engine. When the motive liquid or starting liquid has been all so returned the pump will operate idly until a quantity of such liquid is again discharged into the casing or receiving tank 3 by the starting motor in another engine starting operation. 105

The pump mechanism thus far described will serve for the return of the used motive liquid from the receiving tank back to the pressure reservoir, but in practice it is found necessary also to provide some means by 110 which the air in the reservoir may be kept at sufficient pressure. Without such provision being made the pressure of such confined air might decrease, by reason, for example, of its being first absorbed by the motive liquid and later released to the atmosphere. The 115 pump, therefore, is adapted to replenish the air within the pressure reservoir, as well as to return the used motive liquid thereto. This part of the mechanism will now be described.

At each working stroke of the plunger 60 a small 120 quantity of air is caused to be forced into the delivery pipe 4, by first introducing this air within the upturned portion of the pump outlet 7 at a point just beneath the back-pressure or discharge valve 78. The means for introducing air beneath the valve 78 comprise a short pipe 125 or air-conduit 80 extending from the outside of the pump-outlet 7 to a point therein just beneath the valve 78, and an air-inlet valve 81 opening inwardly and seated upon the inner end of the tube 80, and having a stem 82 extending out through the air-inlet tube 80. 130

The main outlet-valve 78 has a downwardly extending sleeve 83 surrounding the tube 80 and provided with ribs 118, and has just under the valve 78 air apertures 119 and forms a guide for the valve 78, while providing ample space between the ribs 118 for the reception of the air which is to be introduced through the tube 80 and its valve 81. The space surrounding the hollow stem or sleeve 83 must be of limited capacity, so as to contain only the limited amount of air which it is desired shall be forced through the valve 78. If the air capacity beneath the valve 78 were too great this space might become filled with air which, on account of its large quantity, would not develop a sufficient pressure from a working stroke of the plunger 60 to open the valve 78. The stem 82 of the valve 81 is shown as having a fluted construction where it passes through the tube 80, this being for the purpose of allowing free ingress of air around the valve-stem. The valve 81 is normally held with a certain pressure upon its seat by a spring 84 coiled about the valve-stem 82 and expansively acting between the outer end of the tube 80 and a pin 85 carried by the valve-stem. The spring 84 holds the valve 81 upon its seat with sufficient pressure so that the valve will not be opened by the suction stroke of the piston 60 in sucking up the motive liquid through the inlet-valve 75. It is apparent, however, that if the valve 81 should be held open during any portion of the suction stroke of the piston 60 that air would enter therethrough and accumulate beneath the valve 78. Accordingly, means are provided for holding the valve 81 open during the last part of the suction stroke of the pump-plunger 60. Such means comprise a lever 86 pivoted at 87 to the lugs 88 at the lower end of the pump-cylinder and arranged to engage at one of its ends beneath the valve stem 82 and at its other end to be engaged, through the medium of an anti-friction roller 89, by a cam or projection 90, shown as carried by and integral with the pump-operating cam 67. The cam 90 is of the proper length, and the cams 67 and 90 are so timed or placed in reference to each other that the cam 90 will act upon the lever 86 only during the last portion of the suction stroke of the pump-plunger 60 and shown as corresponding to about one-fourth of the full stroke of the pump-plunger, the air-inlet valve 81 at all other times remaining closed. The lever 86 is prevented from pressing by its weight upon the valve stem 82 and is returned after being acted upon by the cam 90 by a spring 91, and has its return movement limited by a projection 92 which comes in contact with the lower end of the pump-cylinder. When air is thus introduced beneath the valve 78 it will be compressed by the downward or working stroke of the piston 60 and forced with the liquid from the cylinder 59 through the valve 78 against the pressure from the pressure-reservoir into the pipe 4 and thus carried with the return liquid into the pressure-reservoir, for keeping up the pressure therein. The pressure in the pressure-reservoir is prevented from going above a predetermined maximum by reason of an ordinary safety or blow-off valve 93 connected with the reservoir at its upper portion for the escape of any excess of compressed air. The air blow-off valve 93 may be of any well known construction.

One additional feature of the pump remains to be described. As the pump acts continuously while the

engine is running, it is apparent that as soon as all of the liquid from the receiver has been taken up and returned to the reservoir, that the pump cylinder 59 will become filled with air taken up through the pipe 77 and inlet-valve 75. If this accumulated air be left to remain within the cylinder 59 and in the passage 7 at a time when there is again liquid in the receiver to be returned to the reservoir, it is evident that such entrapped air would act as a cushion for the plunger 60 and would yield to such an extent that it could not be forced out through the outlet-valve 78 by the piston on its working stroke, and the result would be that no liquid would be delivered by the pump. It follows from this that some means must be provided for first removing or voiding this air from the pump cylinder. To this end an arrangement of valves is provided which permits the exit of air while preventing the escape of the liquid. The plunger 60 is provided with an internal bore 94 within the lower end of which is shown as fitted, as by screw threads, a valve-seat and valve-guide 95. An inwardly opening valve 96 cooperates with the valve-seat 95, its stem 97 being guided therein, and being fluted to provide an exit passage for the air. The valve-stem 97 at its outer end is provided with a head or stop 98 limiting the inward movement of the valve 96, and having air-outlet grooves 120, the valve 96 being normally held in open position by a compression spring 99 contained within the bore 94 and acting against the head 98. Ingress of air through the bore 94 and valve 96 is prevented by an upwardly opening check-valve shown as a ball 100 seated above a reduced portion of the bore 94 and held in place by a pin 101, and which operates to prevent entrance of air into the cylinder 59 during the up or suction strokes of the plunger 60. The spring 99 is of the proper strength so as to at all times hold the valve 96 open when air only is contained within the cylinder 59, but so as to permit the valve 96 to close as soon as the valve 96 encounters the increased resistance offered by a liquid. In operation so long as air only is within the cylinder 59, it will be permitted at each downward stroke of the plunger 60 to pass freely out through the open valve 96 and the outwardly opening check valve 100, the last named valve preventing its return during the suction stroke. In this manner the air will soon be exhausted from the cylinder 59, which will then become filled with liquid, the resistance of this liquid operating to close the valve 96, after which the pump will continue to work in the same manner as if the piston 60 had no central bore or valves, but were of one solid piece. The pump is in this manner rendered self-priming.

To prevent the compressed air within the reservoir and in which the power for starting the engine is stored from escaping through the liquid-outlet 5 and reducing the pressure to that of the atmosphere, which would occur after all of the liquid had been used, means are provided for sealing the reservoir so as to always retain a quantity of the liquid therein. Such means comprise a valve cage 102 above the mouth 103 of the pressure reservoir 1 and inclosing the valve seat 104, the cage being provided with openings 105 near its bottom and openings 106 at the top, for the free ingress and egress of air and liquid. A combined valve and float 107 is contained within the cage 102, the valve having a face-

plate 108, which may be of celluloid, for seating upon the valve-seat 104, and the body of the valve being hollow, as shown, to form a float. By this arrangement enough of the liquid is always left remaining within the reservoir 1 to form a secure seal against the escape of air. When the liquid is sufficiently high within the reservoir the float-valve 107 is held up thereby and free egress of the liquid permitted through the openings 105 in the cage 102 and thence through the mouth 103 of the reservoir 1, the valve 9, the outlet 5 and the pipe 2 to the motor. When the liquid is low in the reservoir, the float valve 107 will no longer be supported thereby, but will settle down upon the valve-seat 104, preventing any further escape of liquid from the reservoir and thus always retaining a residual or initial pressure of air within the reservoir. Means for preventing the escape of the air and the consequent reduction of its initial pressure are all the more necessary because this initial pressure is preferably very high and should always be sufficient to operate the starting motor in the engine starting operation.

It is evident that occasions may arise when the power stored within the reservoir will have been exhausted without the engine having been started. Such a result might occur, for example, by reason of a defective spark-plug. In case of such an event it is important that some additional or supplementary means be at hand for starting the engine. For such emergencies a crank 109 is provided. The crank has a sliding block 110 adjustable to a retracted or projected position within the hub or boss 111 of the crank, with a screw 112 for holding it in either position, the drawing showing this block as projected. The block 110 has a bore 113 for fitting over the end of the engine-shaft 24, and is provided with a notch 114 for engaging the pin 73, and when the crank is placed with these parts engaged the engine may be started directly by cranking in the ordinary manner. However, if preferred, instead of cranking the engine directly, the pressure reservoir 1 may be manually recharged. The sleeve 111 of the crank 109 is provided with shoulders 115 and when it is desired to recharge the reservoir of the starting device the notched block 110 is adjusted to its retracted position, as indicated by the screw receiving recess 116. The sleeve 111 will then pass freely over both the pin 73 and the spring 72 on the shaft 24 and permit the shoulders 115 to engage with the flattened hub 117 of the cam 67. When the crank is turned the ratchet-teeth 70 and 71 will permit the cam 67 to rotate and operate the pump without rotating the sleeve 51 or the shaft 24, thus permitting the pressure reservoir 1 to be recharged by hand independently. This recharging requires so little effort that it may be done by a child.

The reservoir 1 may be initially filled with compressed air, or the pressure may be increased therein or restored to normal high pressure, by pumping or otherwise admitting compressed air through the blow-off valve 93.

It is obvious that various modifications may be made in the construction shown and above particularly described within the principle and scope of my invention.

I claim:

1. In a starter for engines, the combination of a hydraulic motor, means engageable only in one direction of movement for connecting the motor to the engine to start

the engine, a source of motive liquid under pressure connected to the motor, and means for returning the used motive liquid to its source.

2. In a starter for engines, the combination of a hydraulic motor, means engageable only in one direction of movement for connecting the motor to the engine to start the engine, a source of motive liquid under pressure connected to the motor, means for starting and stopping the motor, and means for returning the used motive liquid to its source.

3. In a starter for engines, the combination of a hydraulic motor, means engageable only in one direction of movement for connecting the motor to the engine to start the engine, a source of hydraulic pressure connected to the motor, manually operable means for controlling the engine-starting operation of the motor, and means automatically operated by the engine for continuously returning the used motive liquid to its source during the operation of the engine.

4. In a starter for engines, the combination of a pressure reservoir, a hydraulic motor connected to receive motive liquid from the reservoir and operatively connected to the engine shaft, manually operable means for controlling the engine-starting operation of the motor, a receiver into which the motor discharges, and means for returning the liquid to the reservoir at a relatively constant and less rate than it is discharged by the motor during the engine starting operation.

5. In a starter for engines, the combination of a pressure reservoir, a hydraulic motor connected to receive motive liquid from the reservoir, means engageable only in one direction of movement for connecting the motor to the engine to start the engine, manually operable means for controlling the engine-starting operation of the motor, a receiver into which the motor discharges, and an automatically operating pump for returning the liquid to the reservoir.

6. In a starter for engines, the combination of a pressure reservoir, a hydraulic motor connected to receive motive liquid from the reservoir, means engageable only in one direction of movement for connecting the motor to the engine to start the engine, manually operable means for controlling the engine-starting operation of the motor, a receiver into which the motor discharges, and a continuously-acting pump for returning the liquid to the reservoir.

7. In a starter for engines, the combination of a pressure reservoir containing a motive liquid under pressure, a hydraulic motor connected to receive motive liquid from the reservoir, means engageable only in one direction of movement for connecting the motor to the engine to start the engine, manually operable means for controlling the engine-starting operation of the motor, a receiver for the exhaust liquid from the motor, and a pump operated by a moving part of the engine for returning the liquid to the reservoir.

8. In a starter for engines, the combination of a pressure reservoir containing a motive liquid and also containing an elastic fluid under minimum pressure greater than atmospheric pressure, means for preventing the escape of the elastic fluid, a hydraulic motor connected to receive liquid from the reservoir and operatively connected to the engine shaft, manually operable means for controlling the engine-starting operation of the motor, a receiver for the exhaust liquid from the motor, and automatically operated means for returning the liquid to the reservoir at a less rate than it is used by the motor in operation.

9. In a starter for engines, the combination of a pressure reservoir containing a motive liquid and also containing an elastic fluid under minimum pressure greater than atmospheric pressure, means for preventing the escape of the elastic fluid, a hydraulic motor connected to receive liquid from the reservoir and operatively connected to the engine shaft, manually operable means for controlling the engine-starting operation of the motor, a receiver for the exhaust liquid from the motor, and a pump operated by a moving part of the engine for returning the liquid to the reservoir.

10. In a starter for engines, the combination of a pressure reservoir containing a motive liquid under elastic fluid pressure, a hydraulic motor connected to receive liquid

from the reservoir and operatively connected to the engine shaft, manually operable means for controlling the engine-starting operation of the motor, a receiver for the exhaust liquid from the motor, a pump operated by a moving part of the engine for returning the liquid to the reservoir, and automatic means for sealing the reservoir against escape of all of the liquid therefrom, whereby the retained liquid prevents the elastic fluid from escaping from the reservoir.

10. 11. In a starter for engines, the combination of a pressure reservoir containing a motive liquid under elastic fluid pressure, a hydraulic motor connected to receive liquid from the reservoir and operatively connected to the engine shaft, manually operable means for controlling the engine-starting operation of the motor, a receiver for the exhaust liquid from the motor, a pump, operated by a moving part of the engine, for returning the liquid to the reservoir, and means by which the engine shaft and the motor are automatically operatively disconnected from each other when the engine outspeeds the motor.

15. 12. In a starter for engines, the combination of a pressure reservoir containing a motive liquid under elastic fluid pressure, a hydraulic motor connected to receive liquid from the reservoir, means engageable only in one direction of movement for connecting the motor to the engine to start the engine, manually operable means for controlling the engine-starting operation of the motor, a receiver for the exhaust liquid from the motor, and a pump operated by a moving part of the engine for returning the liquid to the reservoir.

20. 13. In a starter for engines, the combination of a pressure reservoir containing a motive liquid under elastic fluid pressure, a hydraulic motor connected to receive liquid from the reservoir and operatively connected to the engine shaft, manually operable means for controlling the engine-starting operation of the motor, a receiver for the exhaust liquid from the motor, a pump operated by a moving part of the engine for returning the liquid to the reservoir, means for forcing elastic fluid under pressure into the pressure reservoir, and a safety blow-off valve for the elastic fluid in the reservoir.

25. 14. In a starter for engines, the combination of a pressure reservoir containing a motive liquid under elastic fluid pressure, a hydraulic motor connected to receive liquid from the reservoir and operatively connected to the engine shaft, manually operable means for controlling the engine-starting operation of the motor, a receiver for the exhaust liquid from the motor, a pump operated by a moving part of the engine for returning the liquid to the reservoir, the pump having a liquid outlet connected to the reservoir, and means for introducing elastic fluid into said outlet, whereby the elastic fluid is forced with the liquid into the pressure reservoir.

30. 15. In a starter for engines, the combination of a pressure reservoir containing a motive liquid under air pressure, a hydraulic motor connected to receive liquid from the reservoir and operatively connected to the engine shaft, manually operable means for controlling the engine-starting operation of the motor, a receiver for the exhaust liquid from the motor, a pump operated by a moving part of the engine for returning the liquid to the reservoir, the pump having a liquid outlet connected to the reservoir, an upwardly opening delivery valve in said outlet, an air-inlet valve beneath the delivery valve, and means, operated by a moving part of the pump, for holding the air-inlet valve open during the last portion of the suction stroke of the plunger.

35. 16. In a starter for engines, the combination of a pressure reservoir containing a motive liquid under elastic fluid pressure, a hydraulic motor connected to receive liquid from the reservoir and operatively connected to the engine shaft, manually operable means for controlling the engine-starting operation of the motor, a receiver for the exhaust liquid from the motor, a pump operated by a moving part of the engine for returning the liquid to the reservoir, and means for voiding the pump of air without permitting liquid to escape through said means.

40. 17. In a starter for engines, the combination of a pressure reservoir containing a motive liquid under elastic fluid pressure, a hydraulic motor connected to receive

liquid from the reservoir and operatively connected to the engine shaft, manually operable means for controlling the engine-starting operation of the motor, a receiver for the exhaust liquid from the motor, a pump operated by a moving part of the engine for returning the liquid to the reservoir, the pump comprising a cylinder and a plunger therein, the pump having an air escape opening leading from the interior to the exterior of the cylinder, a valve permitting the passage of air from the cylinder outward through said opening and preventing such passage of liquid, and a check valve to prevent air from flowing into the cylinder through said opening, whereby when the pump becomes filled with air the air will be voided without permitting the escape of the liquid.

45. 18. In a starter for engines, the combination of a pressure reservoir, a hydraulic motor connected to receive motive liquid from the reservoir and operatively connected to the engine shaft, manually operable means for controlling the engine-starting operation of the motor, a receiver into which the motor discharges, and a pump for returning the liquid into the reservoir, the pump having a ratchet connection with the engine shaft, whereby the pump may be operated independently of the operation of the engine.

50. 19. In a starter for engines, the combination of a pressure reservoir, a hydraulic motor connected to receive motive liquid from the reservoir and operatively connected to the engine shaft, manually operable means for controlling the engine-starting operation of the motor, a receiver into which the motor discharges, a pump for returning the liquid into the reservoir, the pump having a ratchet connection with the engine shaft, whereby the pump may be operated independently of the operation of the engine, and a crank adapted to be severally operatively connected to the pump and to the engine.

55. 20. In a starter for engines, the combination of a pressure reservoir containing a motive liquid and an elastic fluid under a minimum pressure greater than atmospheric, a hydraulic motor connected to receive the liquid from the reservoir and operatively connected to the engine shaft, means for manually controlling the engine starting operation of the motor, a receiver for the exhaust liquid from the motor and automatically operating means for returning the motive liquid from the receiver to the reservoir.

60. 21. In a starter for engines, the combination of a pressure reservoir containing a motive liquid under elastic fluid pressure, a hydraulic motor connected to receive liquid from the reservoir, a directional clutch connecting the motor to the engine shaft, means for starting and stopping the motor, a receiver for the exhaust liquid from the motor, and a pump, operated by a moving part of the engine, for returning the liquid from the receiver to the reservoir and for forcing elastic fluid into the reservoir.

65. 22. In a starter for engines, the combination of a pressure reservoir containing a liquid and an elastic fluid under minimum pressure above atmospheric, a hydraulic motor connected to receive motive liquid from the reservoir, a directional clutch for connecting the motor and the engine shaft, a receiver for the exhaust liquid from the motor, a pump, operated by a moving part of the engine, for returning the liquid from the receiver to the reservoir, and means for maintaining the elastic fluid in the reservoir within substantially constant limits of pressure above atmospheric pressure at the minimum and sufficient for the engine starting operation.

70. 23. In a starter for engines, the combination of a pressure reservoir containing a liquid and an elastic fluid under minimum pressure above atmospheric, the reservoir having an outlet for the liquid, means for preventing the elastic fluid from escaping through the liquid-outlet, a hydraulic motor connected to receive motive liquid from the liquid-outlet of the reservoir, a directional clutch for connecting the motor and the engine shaft, a receiver for the exhaust liquid from the motor, a pump, operated by a moving part of the engine, for returning the liquid from the receiver to the reservoir, means for maintaining the elastic fluid in the reservoir within substantially constant limits of pressure, means for automatically

priming the pump with liquid, and means for operating the pump independently of the operation of the engine shaft.

24. An engine starter comprising a hydraulic power-storing device, means for connecting the power-storing device with an engine to start the engine, and means continuously operated by the engine to store power in the power-storing device at a less rate than power is used in starting the engine.

10 25. In a starter for engines, the combination of a pressure reservoir, a hydraulic motor connected to receive motive liquid from the reservoir and operatively connected to the engine shaft, manually operable means for controlling the engine-starting operation of the motor, a receiver into which the motor discharges, and means for automatically taking the exhaust liquid from the receiver at a less rate than it is discharged thereinto by the motor during an engine starting operation and returning the liquid into the pressure reservoir.

20 26. In a starter for engines, the combination of a pressure reservoir containing a motive liquid and also containing an elastic fluid under minimum pressure greater than atmospheric pressure, means for preventing the escape of the elastic fluid, a hydraulic motor connected to receive liquid from the reservoir and operatively connected to the engine shaft, manually operable means for controlling the engine-starting operation of the motor, a receiver for the exhaust liquid for the motor, and means for automatically taking the exhaust liquid from the receiver at a less rate than it is discharged thereinto by the motor during an engine starting operation and returning the liquid into the pressure reservoir.

25 27. In an engine starter, the combination of a pressure reservoir containing a motive liquid and also containing an elastic fluid under minimum pressure sufficiently above atmospheric pressure for the engine starting operation, a hydraulic motor connected to receive motive liquid from the reservoir and operatively connected to the engine to start the engine, and means for preventing the pressure

40 of the elastic fluid from being reduced below the minimum.

28. In an engine starter, the combination of a pressure reservoir containing a motive liquid and also containing

an elastic fluid under minimum pressure sufficiently above atmospheric pressure for the engine starting operation, a hydraulic motor connected to receive motive liquid from the reservoir and operatively connected to the engine to start the engine, means for returning the used motive liquid to the reservoir, and means for preventing the pressure of the elastic fluid from being reduced below the minimum.

29. In an engine starter, the combination of a pressure reservoir containing a motive liquid and also containing an elastic fluid under minimum pressure above atmospheric pressure, a hydraulic motor connected to receive motive liquid from the reservoir and operatively connected to the engine to start the engine, and means assuring the retention of a liquid seal within the reservoir to prevent the escape of the elastic fluid therefrom.

30. An engine starter comprising a reservoir containing liquid under pressure, means for using the liquid to start the engine, and means continuously operated by the engine for returning the used liquid to the reservoir at a less rate than such liquid is used in starting the engine.

31. In a starter for engines, the combination of a pressure reservoir containing a liquid and an elastic fluid under minimum pressure above atmospheric pressure, a hydraulic motor connected to receive motive liquid from the reservoir, a directional clutch for connecting the motor and the engine shaft, a receiver for the exhaust liquid from the motor, a pump, operated by a moving part of the engine, for returning the liquid from the receiver to the reservoir, means for forcing elastic fluid under pressure into the pressure reservoir, means for preventing the pressure in the pressure reservoir from rising above a predetermined maximum, and means for preventing the pressure in the pressure reservoir from being reduced to that of the atmosphere.

In testimony whereof I have affixed my signature in presence of two witnesses.

CLYDE J. COLEMAN.
